UNITED STATES PATENT OFFICE.

LAWRENCE V. CALHOUN, OF LIMA, OHIO, ASSIGNOR TO THE DAYTON MALLEABLE IRON COMPANY, OF DAYTON, OHIO, A CORPORATION OF OHIO.

SEALING LOCK AND DOOR STARTER.

Application filed September 2, 1922, Serial No. 586,017. Renewed July 27, 1925.

To all whom it may concern:

Be it known that I, LAWRENCE V. CALHOUN, a citizen of the United States, residing at Lima, in the county of Allen and State of Ohio, have invented certain new and useful Improvements in Sealing Locks and Door Starters, of which the following is a specification.

The principal object of the present invention is to provide a door operating mechanism comprising means for controlling the movements of the door operating lever. A further object is to provide means for preventing the parts of the door mechanism from swinging outwardly away from the car. The limitations imposed upon the clearance at each side of a railway car make it necessary to prevent appliances attached to the car walls from swinging outwardly beyond the allowable limits of this clearance when the car is passing around a curve or when a side sway is set up due to a rough track, and this object is attained in the present invention by providing means for maintaining the parts of the door operating and locking mechanism in position adjacent to the plane of the car wall.

The various objects and advantages of the invention will appear more clearly from the following specification taken with the accompanying drawings in which several embodiments are illustrated. In the drawings,

Fig. 1 shows a partial side elevation of a railway car and a door with the locking mechanism of the present invention applied thereto;

Fig. 2 shows a horizontal section on the line 2—2 of Fig. 1 looking in the direction of the arrows;

Fig. 3 shows a horizontal section on the line 3—3 of Fig. 1 looking in the direction of the arrows;

Fig. 4 shows a vertical section on the line 4—4 of Fig. 1 looking in the direction of the arrows;

Fig. 5 shows a vertical section on the line 5—5 of Fig. 1 looking in the direction of the arrows;

Fig. 6 shows a perspective view of the locking bracket or casing which is secured to the door jamb;

Fig. 7 shows a perspective view of the door operating lever;

Fig. 8 shows a perspective view of the

bracket on which the door operating lever is mounted;

Fig. 9 is a perspective view of the locking bolt;

Fig. 10 shows a partial side elevation of the door operating lever and bracket, illustrating a modified device for controlling the movement of the lever;

Fig. 11 is a sectional view on the line 11—11 of Fig. 10;

Fig. 12 shows a partial side elevation similar to that of Fig. 10 illustrating a third form of the means for controlling the movement of the lever;

Fig. 13 is a sectional view on the line 13—13 of Fig. 12 looking in the direction 70 of the arrows;

Fig. 14 is a view similar to Fig. 10 showing a fourth form of the device for controlling the movement of the lever; and

Fig. 15 is a sectional view on the line 75 15—15 of Fig. 14 looking in the direction of the arrows.

The invention is shown in connection with a car door 20 adapted to close the usual door opening in the side wall 21 of a railway car. One horizontal edge of the door is mounted to travel on a track and the other horizontal edge travels in a horizontal guideway in the usual manner so that the door moves horizontally along the car wall when travelling 80 to or from the closed position illustrated in Fig. 1. The leading edge of the door is adapted to seat against a door jamb 22 which is secured to the outer side of the usual door post 23 extending vertically at the side of 85 the door opening. The face 22^a of the door jamb is offset from the inner parallel face of the door post so that the edge of the door is adapted to overlap the door post as shown at 24. The inside sheathing 25 and the outside sheathing 26 of the car wall are secured to the door post 23 in the usual manner, and a filler plate 27 is inserted between the outside sheathing and the door jamb as shown 90 particularly in Fig. 2. A metal plate 28 is secured to the outer face of the door jamb 22 and extends vertically thereof, being arranged to project beyond the face 22^a of the door jamb, thus forming a vertical guideway to receive the leading edge of the door. 100

The door 20 is operated by a lever 30 having an aperture 31 which is pivotally engaged by a pin or bolt 32 passing through

the outer flange 33^a and the inner plate 33^b of a bracket 33. This bracket seats upon a plate 34 secured to the outer side of the car door and is secured to the door by rivets 35 passing through the bracket and the door and also preferably through a plate 36 located on the inner side of the car door. The aperture 31 in the lever 30 is somewhat loosely engaged by the bolt 32 and has some freedom of movement between the flanges 33^a and 33^b of the bracket so that it can be swung outwardly to some extent away from the car door during the operation of the locking mechanism as hereinafter described. 15 The body portion of the lever 30 is provided with two vertical apertures 37 and 38 of rectangular cross-section which are formed through the enlarged parts 38 and 39 thereof respectively. Reinforcing ribs 40 extend longitudinally of the lever. A vertical flange 41 extends inwardly from the lever adjacent the aperture 37, and two other spaced flanges 42 extend inwardly from the lever adjacent the aperture 38 for purposes 20 hereinafter described.

The door operating lever 30 is adapted to engage a locking bracket or casing 45 which seats upon the outer side of the plate 28 secured to the door jamb. This bracket 25 comprises a base plate 46 which seats upon the plate 28, being provided with a downwardly extending flange 46^a and a laterally extending flange 46^b which have apertures 47 and 48 therethrough respectively, adapted 30 to be engaged by bolts 49 and 50 respectively which extend inwardly through the door jamb and through the door post. This bracket is further provided with two outwardly extending bosses 51 and 52 which 35 have vertical aligning apertures 53 and 54 extending therethrough respectively, these apertures being of substantially the same size as the apertures 37 and 38 in the lever 30. The bosses 51 and 52 are spaced apart 40 vertically to leave an intervening slot or notch 55 adapted to receive the lever 30, and the aligning apertures 53 and 54 are adapted to receive a vertically slideable locking member or bolt 56 which may engage either one 45 of the apertures 37 or 38 formed through the lever. The locking member 56 has an outwardly turned flange 57 at the upper end thereof which overlaps the upper boss 51 and limits the downward movement of the 50 locking member. The member 56 is further provided with a longitudinal slot 58, adapted to be engaged by a bolt 59 which extends through the aperture 60 in the walls of the boss 51 and thence horizontally through the 55 door jamb and the door post, as shown particularly in Figs. 2 and 5.

The base plate 46 of the bracket 45 is further provided with a flange 62 projecting outwardly from the inner edge thereof 60 between the bosses 51 and 52. When the

aperture 37 in the lever 30 is engaged by the locking member 56, the flange 41 of the lever engages the inner surface 62^a of the flange 62, thus holding the door against movement and relieving the strain upon the locking 70 member 56. When the aperture 38 in the locking lever 30 is engaged by the locking member 56, thus holding the door in a partially open position, the flanges 42 of the lever engage the opposite sides of the flange 75 62 and thus provide a rigid connection between the casing 45 and the locking lever when the door is in that position.

The locking member 56 may be secured in its lower-most position by means of the usual car seal 64 which engages the slots 65 in the sides of the boss 52 and a similar slot 66 which passes through the lower part of the member 56. The lower part of the locking member 56 is also provided with an aperture 67, which intersects the slot 66, and an opening 68 is provided in the outer wall of the boss 52 to register with the opening 67 when the member 56 is in its lower position so that access can be had to parts of the car seal within the boss 47, for convenience in removing the parts of a broken seal, for example. A more secure locking of the member 56 may be effected by means of a padlock 70 which is adapted to engage registering apertures in the ears 71 and 72 which are formed on the casing 45 and the bolt 56 respectively, as shown particularly in Fig. 1.

The positive opening and closing movements of the door, when it is near the door post, are effected through the upward extending arm 75 of the lever 30. This arm extends between the flanges 76 of a rod or latch member 77 and is pivotally connected thereto by means of a bolt or rivet 78. The web 79, which unites the flanges 76, is V-shaped in cross-section, as shown in Fig. 1, so that it engages the inclined arm 75 and prevents the rod 77 from swinging downwardly out of a position substantially parallel to the lever 30. The rod 77 is provided with an enlarged head 80 having a notch or recess 81 cut in the under side thereof to engage the boss 82 formed on the upper part 105 of the casing 45 around the aperture which is engaged by the bolt 59. When the notch in the rod 77 engages this boss 82, an operating connection is formed between the rigid door boss and the pivot 32 of the lever 30, 110 so that when this lever is swung outwardly from the notch 55 of the casing 45, after upward movement of the locking member 56 to the extent permitted by the slot 58, the pivotal movement of the lever 30 then operates to effect a positive movement of the door toward or away from the door jamb 22.

When the door is in a partially open position, the rod 77 is supported in a position substantially parallel to the lever 30 by the 115

V-shaped web 79 and as the door reaches a position near the door post, the rod 77 can be swung upwardly from the lever to cause the notch 81 thereof to engage the boss 82, 5 whereupon an upward swinging of the lever will effect a positive movement of the door toward the door jamb. In a similar way the downward swinging of the lever with the notch 81 engaging the boss 82 will effect a positive movement of the door away 10 from the door jamb.

When the operating lever 30 is not secured to the casing 45 by the locking bolt 56, the loose pivotal connection of this lever 15 with the bracket 33 might permit it to swing outwardly from the car door beyond the limits of the allowable clearance, if means be not provided for overcoming this possibility, and the outer flange 33^a of the 20 bracket 30 is therefore provided with a downwardly extending part 85 having an inturned lug 86 at the lower end thereof which is adapted to co-act with the outer face 87 of the lever 30 when the lever is 25 suspended in a vertical position, as shown by dotted lines in Fig. 1. The lug 86 is provided with a rounded surface 86^a which engages the edge of the lever 30 as it swings to its suspended vertical position, thus forcing 30 the lever inwardly so that it is held in a position parallel to the car door. When the lever is in this position, injury to the car door by the flanges 41 and 42 of the lever 30 is prevented by a plate 88 which is 35 secured to the car door by screws 89 and engaged by the inner extremity of the flange 42.

A modified form of the construction for preventing the outward swinging of the 40 lever is illustrated in Figs. 10 and 11 where a lever 90, similar to the lever 30 in construction, is loosely pivoted on a bolt 91 extending between the flanges 92^a and 92^b of a bracket 92. In this construction the flange 92^a has a downwardly extending part 93 provided with an inturned lug 94 having the inner surface thereof inclined as shown at 94^a so that this inclined surface is adapted 45 to engage the surface 95 of the lever 90 and positively force the lever inwardly toward the car door as it swings to its vertical position, thus maintaining the flange 96 of the lever in contact with the plate 97 secured to the car door.

50 A third form of the lever controlling device is illustrated in Figs. 12 and 13 where a lever 98, similar to the lever 30, is mounted between the flanges 99^a and 99^b of a bracket 99, being pivoted on a bolt 100 which extends through these flanges and through the car door 101. In this construction the downwardly extending projection on the bracket is dispensed with and a lug 102 is formed on the inner side of the flange 99^a to 55 co-act with a lug 103 formed on the adjacent

face of the lever 98. These lugs are provided with co-acting inclined surfaces 104 and 105 which engage each other to force the lever toward the car door with the inwardly projecting flange 106 of the lever 70 co-acting with the wear plate 107 secured to the car door. These lugs having the co-acting inclined surfaces are out of engagement with each other when the lever 98 is in the position to be swung outwardly to 75 be engaged with or disengaged from the locking bracket secured to the door jamb, but as the lever approaches its downward vertical position, the lugs engage each other and gradually force the lever inwardly to 80 hold it against outward swinging away from the car door.

A fourth modification of the invention is illustrated in Figs. 14 and 15 where a lever 110, similar to the lever 30, is pivoted 85 on a bolt 111 extending through the flanges 112^a and 112^b of a bracket 112 secured to the car door 113. In this construction both the inner and outer flanges of the bracket are provided with downwardly extending 90 parts having inturned lugs 114 and 115 formed on the lower ends thereof. These lugs are provided with inclined surfaces 116 and 117 adapted to receive the lever 110 when it swings to its suspended vertical 95 position. These inclined surfaces engaging opposite sides of the lever force the lever into a position parallel and in proximity to the car door with the projecting flange 118 of the lever held out of engagement with 100 the car door so that the use of a wear plate is unnecessary.

Although several forms of the invention have been shown and described for purposes of illustration, it will be understood that 105 the improvement may be embodied in various forms of construction without departing from the scope of the appended claims

I claim:

1. In combination, a frame member, a door, 110 a pivotally mounted lever, said lever having limited swinging movement transverse to the pivotal movement thereof, means for locking said lever to secure said door to said frame member, and fixed with reference to 115 the pivotal mounting of the lever, means for restraining the outward movement of said lever in said transverse direction when it is disconnected from said locking means.

2. In combination, a frame member, a 120 door, an operating member pivoted on said door, means for locking said operating member to said frame member, and means fixed relatively to the door to restrain the swinging of said operating member away from 125 said door when it is disconnected from said locking means.

3. In combination, a frame member, a 130 door, an operating member pivoted on said door, means for locking said operating mem-

ber to said frame member, and fixed means on the door adapted to engage said lever for preventing the swinging thereof away from said door when it is disconnected from said locking means and suspended from its pivotal connection.

4. In combination, a frame member, a door, locking means for connecting said frame member and said door, said locking means comprising a pivotally mounted lever, and means adapted to engage said lever as it reaches a suspended position for forcing said lever inwardly toward the plane of the door.

10 5. In combination, a frame member, a door, a lever pivoted on said door, means for locking said lever to said frame member, means for holding said lever in a position adjacent to said door when it is disconnected from said locking means, and a plate adapted to engage the inner side of said lever and prevent contact thereof with said door.

15 6. In combination, a bracket, a lever loosely pivoted on said bracket, and means carried by said bracket for engaging said lever and limiting its swinging movement in planes parallel to its pivotal axis.

20 7. The combination in a door locking mechanism of a supporting member, a lever loosely pivoted on said supporting member for limited swinging movement in a plane at an angle to the plane of its pivotal movement, and means adapted to engage the outer side of said lever when it is suspended from its pivotal connection for positively preventing said limited swinging movement.

25 8. The combination in a door locking mechanism of a supporting member, a bracket mounted on said supporting member and having parallel flanges, a lever

swingingly mounted between said flanges for movement parallel to and laterally of said flanges, and means extending downwardly from the outer flange of said bracket 45 for engaging the outer surface of said lever as it reaches a suspended position beneath said bracket and thereby positively preventing the lateral swinging thereof.

9. The combination in a door locking 50 mechanism of a bracket having an outwardly spaced flange, a lever loosely pivoted between said flange and the body of said bracket and a lug carried by said flange and provided with a cam surface adapted to engage said lever and prevent the outward swinging thereof in a predetermined position.

10. The combination in a door locking mechanism of a bracket, a lever loosely pivoted on said bracket and having a flange projecting inwardly therefrom and spaced from said pivotal connection, a plate adapted to engage said flange when said lever is in a suspended position, and a lug carried 60 by said bracket and adapted to co-act with the outer side of said lever to force said flange inwardly toward said plate.

11. In an operating and locking mechanism for a sliding door member having a 70 door frame member associated therewith, the combination with a lever swingingly supported on one of said members; of a pulling element operatively connected to said lever, and adapted to be attached to the other 75 member; means for locking said lever to the last named member to lock the door; and means adapted to engage said lever when in pendant position for positively preventing outward swinging movement away from the 80 door member.

LAWRENCE V. CALHOUN.
